METHOD OF MAKING WELTING

William C. Vizard, Brockton, Mass., assignor to
 Barbour Welting Company, Brockton, Mass., a
 partnership

Application September 10, 1940, Serial No. 356,174

4 Claims. (Cl. 12—146)

This invention relates to the manufacture of shoe welting, and pertains more particularly to leather welting characterized by unusual thickness along the welt extension which is outseamed to the usual outsole to furnish a heavy edge effect in a single soled shoe made with a welt of this type.

As suitable welting leather of adequate thickness for this purpose is not readily available, heavy edge welting has heretofore been prepared by superposing separate strips to produce a two unit welt as disclosed in Lyon Patents 1,708,628 and 1,708,629, or by center folding a double width fillet as shown in Gilson Patent 1,732,807.

It is accordingly the principal purpose of the present invention to provide a welt suitable for heavy edge, single soled shoes by forming an oblique slit in the grain side of a relatively wide fillet, parallel to and remote from a longitudinal edge thereof, and then folding the fillet upon itself and fastening the juxtaposed flesh surfaces together, to produce a heavy edge welt substantially wider than one-half the width of the fillet and having an inclined flesh shoulder which closely hugs the upper at the crease of the shoe, and a beveled sewing edge which yields readily under welt beating for proper inseaming, thereby affording appreciable economies in production and simplifying shoe manufacture.

Another purpose of the invention is to enhance the appearance and increase the surface width of the welt extension of the improved double edge welting, by skiving a thin scarf or ribbon from the exposed, shell-like grain surface of the deck produced by folding an obliquely slit fillet as above described.

A further object of the invention is to form a flat inseam ledge and an abrupt, upper-hugging shoulder adjacent the fold of the fillet, by making a short lateral cut at the inner end of the inclined slit above mentioned.

These and other features of the new welting and its method of manufacture will be more fully explained in the following description of the recommended embodiments of the invention illustrated in the accompanying drawings, and will be pointed out in the appended claims. In the drawings,

Figure 1 is a perspective view of a leather fillet formed with an inclined slit through its grain side;

Fig. 2 is a similar view indicating the manner of folding the fillet upon itself at the hinge defined by the crotch of the slit;

Fig. 3 shows the fillet completely folded with

the juxtaposed flesh surfaces united by cement or otherwise;

Fig. 4 illustrates the preferred manner of skiving off a thin ribbon from the grain surface of the deck of the heavy edge welt extension, and also shows the formation of the inseam groove and the removal of a triangular string from the sewing edge of the welt; the thickness of the removed ribbon and string being exaggerated for the sake of clarity;

Fig. 5 is a perspective view of the molded heavy edge welt, ready for application in shoe manufacture; and

Figs. 6 to 10 are views similar to Figs. 1 to 5, respectively, showing the provision of an additional, lateral slit in the fillet which produces the inseam ledge and shoulder at the folded hinge.

In the particular embodiment of the invention chosen for the purpose of illustration in Figs. 1 to 5 inclusive, the heavy edge welt is produced from a leather fillet 11 (Fig. 1) of rectangular cross-section and of a thickness equivalent to that of ordinary Goodyear welting, approximately $\frac{1}{16}$ inch. The fillet or strip is customarily supplied in rolls of indeterminate length, and the width of the fillet is appreciably less than twice the width of the finished welt; for example, a heavy edge welt (Fig. 5) $\frac{1}{2}$ inch in width may be made from a fillet $\frac{3}{32}$ inch wide. The figures of the drawings are approximately twice actual size, and the grain side of the leather is indicated by stippling.

The fillet 11 is slit longitudinally at 12, parallel to and remote from the edge 13 which is to constitute the outer edge of the deck of the doubled welt extension, but nearer to that edge than to the opposite edge 14; the slit entering the top or grain side of the leather, inclining away from the edge 13 at an oblique angle to the plane of the fillet, and terminating adjacent the bottom or flesh side to form a central hinge 15 (Fig. 2) on which the fillet is to be folded upon itself. The slit 12 is preferably incised by a suitable machine (not shown) which is also equipped with rollers for applying cement to the flesh surface 45 of the fillet, and with fingers for folding and pressing together the divided portions 16 and 17 thereof; but it will be understood that these operations may be performed separately, by hand or by mechanical devices.

In either case, the parts 16 and 17 are doubled together on the longitudinal center hinge 15 so that the flesh surfaces thereof are juxtaposed, and the two portions are suitably attached, preferably by cement applied to said flesh surfaces 55

along the line of juxtaposition 18 (Fig. 3). When thus folded and bonded together, the portion 17 constitutes the base of the duplex welting strip, including the tapered or beveled sewing edge 19; the portion 16 constitutes the grain-surfaced deck, having substantially less surface width than the base and presenting an inclined inner edge 20 of flesh stock; and the outer edges 13 and 14 of the two portions are flush and normal to the base.

Although the duplex strip thus formed and as shown in Fig. 3 may be used as a heavy edge welt, the strip is preferably further treated as indicated in Figs. 4 and 5, to provide a better fitting, easier sewing and neater appearing welt.

In order to furnish an exposed grain surface appreciably wider than the surface of the deck 16 of Fig. 3, and also to avoid the shell-like and porous texture of the grain surface thereof, a thin ribbon or scarf 21 is preferably skived from the grain (Fig. 4). Owing to the inclined slope 20 at the inner edge of the deck, the removal of this ribbon will necessarily provide a wider surface 22 free from excessive porosity, without materially reducing the thickness of the edge of the composite welt extension and without destroying the desired fineness and appearance of the grain.

A small triangular string 23 may also be cut from the beveled inner edge of the base 17, to ensure easier and more compact application of the welt to the inlasted upper and insole rib; and the usual inseam stitch receiving groove 24 is formed in the base member of the welting.

Finally, the welt is molded to form smoothly rounded shoulders 25 and 26 along the inclined inner edges of the deck and base respectively; and this operation tends to compress the hinge or fold 15 downwardly and outwardly, as shown in Fig. 5, to form an upper groove 27 for the inseam stitching and to reduce the thickness of the leather between the two grooves 24 and 27. The exposed edges and surfaces of the finished heavy edge welt may be colored as usual to match the color of the upper; and the bottom grain surface of the base 17 may be roughened or thinly skived, if desired, to afford greater flexibility of the sewing edge and better adherence of the welt extension to the outsole on which it is customarily cemented prior to outseaming. It will be understood that the welt is inseamed to the upper and innersole and outseamed to the outsole in the same manner as ordinary Goodyear welting, or as indicated in the aforesaid Lyon and Gilson patents.

In the modified forms of the invention illustrated in Figs. 6 to 10 inclusive, the fillet 11 is provided with a lateral slit 31 in the flesh portion of the strip as well as with the inclined slit 12 previously described. Both slits may be formed simultaneously by an angular shaped knife, if desired, the slit 31 being relatively shallow and extending from the inner end of slit 12 toward the fillet edge 14, parallel to and adjacent the bottom of the leather strip (Fig. 6).

The lateral slit affords a relatively wide longitudinal hinge 32 which enables the portions 16 and 17 to be folded more easily with less likelihood of cracking at the fold (Fig. 7), and also provides an abruptly rounded shoulder 34 and an adjacent flat ledge 35 along the inclined inner edge of the duplex strip (Fig. 8). The upstanding flesh shoulder 34 enables the resulting welt (Fig. 10) to hug the upper more closely at the crease of the shoe to which it is applied; and the crease or groove between the shoulder and the

ledge or shelf 35 serves as a more efficient guide for the inseam stitches.

Except for these desirable and advantageous refinements, the heavy edge welt of Fig. 10 is made in the same manner as described in connection with Figs. 1 to 6.

Integral shoe welting produced in accordance with either illustrated embodiment of this invention avoids the difficulties involved in nicely adjusting and attaching two separate strips or fillets to make the two unit welt of the Lyon patents, and affords substantial savings in leather costs over the unslit, center-folded welting of the Gilson patent. The new heavy edge welt is also easier to apply and shape to the lasted upper for inseam stitching because of the flexible, beveled sewing edge, and fits more closely against the upper after stitching because of the sloping or rounded flesh shoulder at the inner edge of the deck. As is well understood, this type of welting is intended to be used in single-soled Goodyear welt shoes and, although the inner sloping edge of the welt extension tends to support the upper and protect the crease against the elements in the manner of beaded welting, it will be appreciated that the heavy edge welt serves additional purposes not accomplished by the usual forms of beaded or calked welting.

The improved heavy edge welting and the methods of manufacture thereof, as herein illustrated and described, are subject to other variations and modifications to suit particular conditions, without departing from the essence of this invention as defined in the following claims.

I claim:

1. A method of making heavy edge welting which consists in forming a longitudinal slit in the grain side of a leather fillet, so that the slit inclines downwardly and away from one edge of the fillet and terminates approximately midway between the edges and adjacent the bottom thereof to provide a longitudinal hinge, folding the fillet on said hinge so that the flesh surfaces of the folded portions are juxtaposed with the edges thereof substantially flush, and cementing the flesh surfaces of the two portions together, to provide a strip of welting having a base formed with an inclined sewing edge and a deck formed with a sloping flesh edge adapted to engage a shoe upper.

2. A method of making heavy edge welting which consists in forming a longitudinal slit in the grain side of a leather fillet, so that the slit inclines downwardly and away from one edge of the fillet and terminates approximately midway between the edges and adjacent the bottom thereof to provide a longitudinal hinge, folding the fillet on said hinge so that the flesh surfaces of the folded portions are juxtaposed with the edges thereof substantially flush, cementing the flesh surfaces of the two portions together, to provide a strip of welting having a base formed with an inclined sewing edge and a deck formed with a sloping flesh edge adapted to engage a shoe upper, and skiving a thin ribbon from the grain surface of the deck to increase the width of the exposed deck surface.

3. A method of making heavy edge welting which consists in forming a longitudinal slit in the grain side of a leather fillet, so that the slit inclines downwardly and away from one edge of the fillet and terminates approximately midway between the edges and adjacent the bottom thereof to provide a longitudinal hinge, folding the

fillet on said hinge so that the flesh surfaces of the folded portions are juxtaposed with the edges thereof substantially flush, cementing the flesh surfaces of the two portions together, to provide 5 a strip of welting having a base formed with an inclined sewing edge and a deck formed with a sloping flesh edge adapted to engage a shoe upper and skiving a thin ribbon from the grain surface of the deck to increase the width of the exposed 10 deck surface, and molding the strip to round the sloping flesh edge of the deck and the inclined sewing edge of the base, and to form a stitch-receiving groove therebetween.

4. A method of making heavy edge welting 15 which consists in forming a longitudinal, laterally inclined slit in the grain side of a leather fillet, so that the slit extends oblique to the plane of

the fillet and terminates approximately midway between the edges and adjacent the bottom thereof, forming a shallow lateral slit leading from the end of the first slit parallel to the plane of the fillet, to provide a relatively wide hinge in the 5 flesh side thereof, folding the fillet on said hinge so that the flesh surfaces of the folded portions are juxtaposed with the edges thereof substantially flush, and cementing the flesh surfaces of the two portions together, to provide a strip of 10 welting having a base formed with an inclined sewing edge, a deck formed with a sloping flesh edge adapted to engage a shoe upper, and a rounded shoulder and adjacent flat ledge forming a stitch-receiving crease therebetween. 15
